PICKER FOR FLY SHUTTLE LOOMS

George M. Huguley, Clinton, S. C.

Application June 19, 1950, Serial No. 168,973

10 Claims. (Cl. 139—159)

1

This invention relates to improvements in pickers for fly shuttle looms, and more particularly to improve adjusting and clamping means for securing a loom picker in desired position of adjustment on the picker stick and for effecting ready replacement of a worn picker.

As is well known, the flight of the shuttle employed in fly shuttle looms is checked in part by friction at several points in the shuttle's flight, namely, between the front box plate and the binder, by the usual picker stick check mechanism, and finally by the picker itself, which is usually a reinforced rubber or leather stop mounted on the picker stick in line with the flight of the shuttle. Obviously, proper shuttle operation requires that the recessed cone opening of the picker must be exactly centered with the shuttle nose or point, so that all pickers on present looms have to be paralleled to the shuttle flight, which is an exceedingly difficult and time-consuming operation. Moreover, replacement of a worn picker on present looms usually requires removal of the picker head or frame from the picker stick, with the result that picker must be centered with the flight of the shuttle every time the picker is replaced.

A principal object of the present invention is to provide a picker which, when once properly adjusted on the picker stick, requires no further adjustment for the life of the picker stick, and which moreover permits the picker to be replaced as may be necessary without any requirement of further adjustment to parallel or center its cone-shaped opening with the flight of the shuttle.

Another object of the invention is to provide improved picker securing means that can be applied to the picker stick without injury thereto.

A further object of the invention is to provide improved picker clamping means which allows quick replacement of a worn picker, while at the same time insuring accurate alignment and centering of the replacement picker.

Still another object of the invention is to improve generally upon the construction and operation of pickers for fly shuttle looms.

An ancillary object of the invention is the provision of picker clamping means which permits the use of a cheaper picker through the facilitated operation of mounting the picker insert when replacement thereof is required.

A more detailed object of the invention is the provision of an improved and inexpensive picker for fly shuttle looms which may be readily secured in desired position of vertical adjustment

2

on a picker stick, which simplifies the replacement of a picker insert while at the same time assuring that the new picker is properly centered with the shuttle's flight, and which is thoroughly dependable in its operation.

The above and other objects and features of advantage of the improved loom picker according to the present invention will be apparent from the following detailed description, taken with the accompanying drawings illustrating a preferred form thereof, in which—

Fig. 1 is a side elevation of the improved picker according to the invention, mounted on a conventional picker stick;

Fig. 2 is a plan view of the improved picker, the view being taken on line 2—2 of Fig. 1; and

Figs. 3 and 4 are rear and front end views, respectively, of the picker illustrated in Figs. 1 and 2.

Referring to the drawings, wherein like reference characters designate like parts throughout the several views, reference character 10 generally indicates a rectangular picker head or frame defining a socket-like through opening whereby it can be slipped over the upper end of the picker stick 12 and shifted therewith to desired position. The frame opening has width corresponding generally to the thickness of the picker stick plus slight clearance, and length which is somewhat greater than the width (horizontal dimension in Fig. 1) of said picker stick. To secure the frame 10 in desired position of vertical adjustment on the picker stick, the frame mounts within its opening a vertically-tapered securing plate 14 which extends between the sides of the frame. Preferably, the plate is hardened and its inner face is formed with a plurality of horizontally disposed serrations 16 providing sharpened edges adapted to bite into the rear vertical edge of the picker stick. The plate 14 is normally loose and movable relative to the frame 10, but pressure may be applied to it by a set screw 18 threaded through the rear vertical wall of the frame, the screw having a pointed inner end

adapted when screwed down to bear against the plate with pressure sufficient to cause the edges of the serrations 16 to bite into the picker stick, thereby to firmly attach the frame thereto. A lock nut 20 threaded on to the outer end of the set screw functions to prevent turning of the set screw and thereby locks the frame in the position to which it has been adjusted as aforesaid.

The frame 10 mounts forwardly (inwardly) thereof the picker or stop member 22, to be hereinafter sometimes referred to as an insert

picker, which is provided in its front vertical face with a cone-shaped recess 24 adapted to be centered with the flight of the loom shuttle (not shown). As is well known, the picker insert may be formed from a block of reinforced rubber, leather, or composition material, or from plies thereof which are suitably secured one to the other.

According to the invention, the picker insert 22 is clamped to the picker frame 10 by clamping means including a pair of clamping arms 26, 28 adapted to turn on vertical axes provided by pivot bolts 30, 32 passing through the intermediate portion of said arms and extending vertically between pairs of vertically spaced ears or wings 34, 34a which project outwardly from the sides of the frame. Preferably, the bolts thread into the openings of the upper ears or wings, such resulting in the bolts being firmly secured to the frame against unintentional removal. However, the remaining length portions of the bolts are unthreaded and pass through on-size holes in the clamping arms so that the arms may turn freely on the axis of the bolts, but without any side play or lost motion.

By reference to Figs. 1 and 2, the inner ends of the clamping arms may be slightly offset outwardly and they terminate in vertically disposed clamping jaws 26a, 28a which project forwardly (inwardly) of the picker frame 10 by an amount not exceeding the horizontal depth dimension of the picker insert 22. The adjacent clamping faces of said jaws may be serrated or otherwise roughened so as to exert a firm grip on the side faces of the insert picker acted upon by said jaws.

The outer (rear) ends 26b, 28b of said clamping arms also extend substantially beyond the frame 10 and their outer terminals are provided with drilled and tapped holes 36, 36a disposed in transverse alignment. Said holes receive a jaw actuating screw 38 which is threaded one half with righthand threads, and the other half with lefthand threads, the screw being also provided at both ends with slots 40, 40a each adapted to receive a screw driver or similar tool by which the screw can be turned from either end, so as to spread or contract the outer ends of the clamping arms aforesaid. Locking nuts 42, 42a threaded on to the ends of the actuating screw 38 are adapted to lock against the side faces of the clamping arms, thus to prevent any slippage or unloosening of the screw following turning thereof as aforesaid.

By reference to Figs. 1 and 2, the frame 10 is provided with a ledge 44 overhanging its front face against which the insert picker 22 engages. Said ledge is preferably formed integral with the frame, but it may be provided by a cross bar welded or otherwise secured against the top edge of the frame front wall, as illustrated. The purpose of the ledge 44 is to provide an abutment shoulder or stop for the upper rear edge portion of the insert picker, which locates the latter vertically with respect to the frame and also prevents any vertical shift of the insert picker under the throw of the picker arm.

While it is believed that the functioning of a picker as described and illustrated will be clear to those skilled in the art, such will nevertheless be described briefly. When it is desired to mount the picker on the picker stick, the frame 10, with securing plate 14 loose therein, is slipped over the end of the picker stick to a desired vertical position thereof, whereupon the

set screw is screwed home against said plate and applies pressure thereto, thus firmly attaching the frame to picker stick. Upon tightening of lock nut 20, the frame mounting operation is complete. At this point, it will be observed from Fig. 1 that while the securing plate 14, set screw 18 and lock nut 20 are disposed to the same end of the frame as the operating ends 26b, 28b of the clamping jaws and are moreover contained between said operating ends and the actuating screw 38, said first-named parts are vertically offset from the latter parts, as seen in Fig. 2, and hence may be freely manipulated without interference from said operating ends and actuating screw.

To mount the insert picker 22, if such was not already clamped between the clamping jaws 26a, 28a in a prior operation, the actuating screw 38 is turned in direction as to spread the jaws slightly, whereupon the insert picker 22 is placed flat against the front (inner) face of the frame, and so that its upper rear corner engages against the under surface of the ledge 44. The actuating screw 38 is now turned in reverse or jaw-closing direction, resulting in the jaw faces clampingly engaging against the side faces of the insert picker, thereby to secure the same in place. By virtue of the fact that the actuating screw 38 effects movement of the clamping jaws in unison, it becomes self-evident that the central recess 24 of the insert picker is always centered on the picker stick and hence is always grooved with the flight of the shuttle.

Thus, it will be clear that once the frame 10 and its clamping means is "set" on the picker stick as aforesaid, its setting is permanent for the life of the stick, no further adjustment thereof being necessary. Moreover, when an insert picker becomes worn, it may be quickly replaced by the simple operations of loosening and tightening the adjusting screw 40, with assurance that the replacement insert will have exactly the same position and centering as the prior insert. The aforesaid permanent setting of the picker frame on stick has the additional advantage that it greatly increases the life of the picker stick, as compared to the prior pickers whose frequent readjustment on stick caused wear and damage, thus shortening the useful life of the picker stick.

As many changes could be made in carrying out the above constructions without departing from the scope of the invention, it is intended that all matter contained in the above description or shown in the accompanying drawings shall be interpreted as illustrative and not in a limiting sense.

I claim:

1. In a loom picker, a picker frame adapted to be slipped over the end of a picker stick, means for securing the frame in a desired position of vertical adjustment on the picker stick, a picker, a pair of clamping jaws mounted on the frame for turning movement about vertical axes and being operative to clampingly engage against the sides of said picker, and means for actuating said jaws in unison toward and away from one another.

2. In a loom picker, a picker frame adapted to be slipped over the end of a picker stick, means for securing the frame in a desired position of vertical adjustment on the picker stick, a picker, a pair of clamping arms pivotally connected intermediate their ends to said frame for turning

movement about vertical axes, said arms terminating at their one ends in vertically disposed jaws adapted to clampingly engage against the sides of the picker, and means operative on the other ends of said arms for actuating said jaws in unison towards and away from one another.

3. In a loom picker, a picker frame adapted to be slipped over the end of a picker stick, means for securing the frame in a desired position of vertical adjustment on the picker stick, a picker, a pair of clamping arms pivotally connected intermediate their ends to said frame for turning movement about vertical axes, said arms terminating at their one ends in vertically disposed jaws adapted to clampingly engage against the sides of the picker, and an actuating screw operative between the other ends of said jaws for actuating said jaws in unison towards and away from one another.

4. In a loom picker, a picker frame adapted to be slipped over the end of a picker stick, means for securing the frame in a desired position of vertical adjustment on the picker stick, a picker, a pair of clamping arms pivotally connected intermediate their ends to said frame for turning movement about vertical axes, said arms terminating at their one ends in vertically disposed jaws adapted to clampingly engage against the sides of the picker, and an actuating screw extending between and threaded into the other ends of said arms, said screw having opposite threads in its end portions whereby rotation thereof effects movement of said jaws in unison toward and away from one another.

5. In a loom picker, a rectangular picker frame adapted to be slipped over the end of the picker stick, means for securing the frame in a desired position of vertical adjustment on the picker stick, a picker, and picker clamping means comprising pairs of vertically spaced ears extending from the sides of said frame, a pair of clamping arms extending along the sides of the frames, each said arm extending through the space between the ears of a pair thereof, pivot means mounted in each pair of ears and passing through the clamping arm extending therebetween, the inner ends of said arms extending beyond the corresponding end of the frame and providing vertically disposed clamping jaws adapted to clampingly engage the sides of the picker, the outer ends of the clamping arms extending beyond the corresponding end of the frame, a jaw actuating screw extending between and threaded into said outer ends, said screw having opposite threads in its end portions whereby rotation of the screw effects movement of the jaws in unison toward and away from one another.

6. A loom picker as set forth in claim 1, wherein in the frame is provided with means for locating the picker vertically and against slippage with respect to the frame.

7. In a loom picker, a rectangular picker frame adapted to be slipped over the end of the picker stick, means for securing the frame in a desired position of vertical adjustment on the picker stick,

65

the frame being provided with a ledge extending across and overhanging an end wall of the frame, a picker disposed against said end wall with its top face engaging the under face of the ledge, and means mounted on said frame and positioned so as to be operative against the side faces of the picker for clamping the picker positioned as aforesaid.

8. In a loom picker, a rectangular picker frame adapted to be slipped over the end of the picker stick, means for securing the frame in a desired position of vertical adjustment on the picker stick, the frame being provided with a ledge extending across and overhanging an end wall of the frame, a picker positioned against said end wall with its top face engaging the under face of the ledge, and a pair of clamping arms pivotally mounted on said frame for turning movement about vertical axes, the inner ends of said arms providing clamping jaws extending beyond said end wall and being operative to clampingly engage against the side faces of said picker thereby to secure the picker in its aforesaid position.

9. In a loom picker, a rectangular frame having an opening for the picker stick, said opening having greater length than the width of the picker stick, a securing plate loosely disposed in and extending across one end of said opening, said plate having a plurality of biting edges on its face adjacent the picker stick, screw means carried by the corresponding end of said frame for applying pressure on said plate thereby to cause said biting edges to bite into the adjacent edge of the picker stick extending through said frame opening and to secure the frame in a desired position of vertical adjustment on said picker stick, a picker engaging against the outer face of the other end of the frame, clamping arms pivotally connected to the frame intermediate their ends for turning movement about vertical axes, said arms terminating at their one ends in vertical clamping jaws adapted to clampingly engage the picker, and screw means operative between the other ends of said arms for actuating said jaws in unison towards and away from one another.

10. A loom picker as set forth in claim 9, wherein the screw means for applying pressure to the securing plate and the screw means for actuating the clamping jaws are disposed to the same end of the picker frame but are offset vertically with respect to one another.
